The ornamental design for a hole patcher for use on wallboard, as shown and described.

DESCRIPTION

FIG. 1 is a front, top and side perspective view of the hole patcher for use on wallboard showing my new design; FIG. 2 is a front elevational view thereof; FIG. 3 is a rear elevational view thereof; and, FIG. 4 is a bottom plan view thereof, the top plan view, the left and right side elevation views all being a mirror image with the exception of the orientation of the bolt as viewed from the sides.
